[57] CLAIM

The ornamental design for surgical saw, as shown and described.

DESCRIPTION

FIG. 1 is a front view of a saw constructed in accordance with the invention;

FIG. 2 is a right side view of the saw;

FIG. 3 is a rear view of the saw;

FIG. 4 is a left side view of the saw;

FIG. 5 is a top view of the saw; and,

FIG. 6 is a bottom view of the saw.

The broken line showing of the power cord in the FIGS. 1 through 6 are for illustrative purposes only and forms no part of the claimed design.

FIG. 1

FIG. 2

FIG. 3

FIG. 4

FIG. 5

FIG. 6
